UNITED STATES PATENT OFFICE.

THOMAS P. ARCHER AND ERNEST E. HEINTZ, OF DETROIT, MICHIGAN, ASSIGNEES
TO TERNSTEDT MANUFACTURING COMPANY, OF DETROIT, MICHIGAN, A CORPORA-
TION OF MICHIGAN.

WINDOW-REGULATOR INSTALLATION.

Application filed June 18, 1924. Serial No. 720,739.

To all whom it may concern:

Be it known that we, THOMAS P. ARCHER and ERNEST E. HEINTZ, citizens of the United States, residing at Detroit, in the county of Wayne and State of Michigan, have invented certain new and useful Improvements in Window-Regulator Installations, of which the following is a specification.

10 This invention relates to a window regulator and has for its object a window regulator which may be detachably connected with the lifting element simply by taking off the window moulding and tipping the window.

However, the connection is so arranged that when the window is in a vertical position the lift cannot disconnect. In other words, when the window regulator and the sash are in their accustomed vertical positions they are locked together, but when one is tilted with respect to the other they can be easily disassembled.

Referring to the drawings:

25 Fig. 1 is a side elevation of a coupé with the window regulator and the sash installed.

Fig. 2 is a cross section through the window post with the window moulding in position.

30 Fig. 3 shows the window moulding removed and the window tipped for disengagement from the regulator.

Figs. 4 and 5 are vertical sectional views of the same character.

35 Fig. 6 is a fragmentary detail of the bottom of the sash and the end of the lift lever.

The invention here is shown in connection with the lever type of window regulator, but it can be used for various other types, such as the chain type, cable type, screw and nut type and practically any type. It is, however, especially well adapted for the lever type of regulator which requires a track or runway on the bottom of the sash in which runs the end of the lever.

Referring to the drawings, *a* designates the lever arm which is provided on its end with a roll *b*. The periphery of this roll is convex in cross section. This is an important factor in connection with the lower sash channel which is provided with an inverted V groove *c*. This permits the win-

dow sash to be tipped and disengaged from the roller, as shown in Fig. 5 when the window moulding *d* has been removed. Preferably, however, in order to effect the removal the roller channel *e* has to be slightly sprung, for when the roller is in an upright position, as shown in Fig. 4, the channel is slightly sprung in order to prevent rattling as it always bears on the roller in an upright position, so as to take up all looseness.

When the window moulding *d* is in place it is impossible for the roller and the channel to separate under any circumstances, hence there is no danger of any accidental disconnection between the parts.

Preferably the window channel is rolled as a single strip forming the window retaining channel and the subtended roller channel. This feature, however, is no part of this invention and is not claimed in this application.

What we claim is:

1. In a window regulator installation, the combination of a window guide provided with means which can be removed to permit the window to tip, a window lift including a lifting lever, a sliding sash guided in the guide and provided with a track along which the lever is slidable, the said lever and track being connected together so that they are locked against disassembly when the window is in a vertical position but permits disassembly at all points where the window can be freely tilted.

2. In a window regulator installation, the combination of a window guide provided with means which can be removed to permit the window to tilt, a window lift, a sliding sash provided with a depending track along which a part of the window lift engages, the said track and the engaging part of the window lift being arranged so that they lock against disassembly in all positions where the window is vertical but they permit disassembly in all positions where the window can be sufficiently tilted.

3. In a window regulator installation, the combination of a window provided with a lower sash bar having a dependent channel, a window lift provided with a roller that runs in the channel, said channel and the roller arranged so that they can be disas-

sembled when the window is tilted laterally and locked against separation when the sash is in a vertical position.

4. In a window regulator installation, the combination of a window provided with a lower sash bar having a dependent channel portion, a window lift provided with a roller secured in the said channel portion by slightly springing the walls thereof.

5. In a window regulator installation, the combination of a window provided with a lower sash having an inverted V groove in the bottom of the sash channel and provided with a dependent channel portion, and a

6. In a window regulator installation, the combination of a window provided with a lower sash having an inverted V groove in the bottom of the sash channel and provided with a dependent channel portion, and a window lift provided with a roller which is convex in cross section at its periphery and which may be disengaged from the sash when the lift and the window are tilted relatively to each other.

6. In a window regulator installation, the combination of a window guide provided with a removable moulding, a window lift provided with a roller having a periphery which is convex in cross section, a sash locked in the guide and provided with a sash bar having a groove in its bottom and having a subtended channel for the roller, said roller disengaged by a relative tilting movement between the sash and the window lift when the moulding is removed, and locked against disengagement when the window is secured in vertical position by the presence of the moulding.

In testimony whereof we have affixed our signatures.

THOMAS P. ARCHER.
ERNEST E. HEINTZ.
